UNITED STATES PATENT OFFICE.

EDWIN F. BROWN, OF CHICAGO, ILLINOIS.

ENVELOP.

No. 856,390.

Specification of Letters Patent.

Patented June 11, 1907.

Application filed April 6, 1903. Serial No. 151,265.

To all whom it may concern:

Be it known that I, EDWIN F. BROWN, a citizen of the United States, residing at Chicago, in the county of Cook and State of Illinois, have invented a certain new and useful Improvement in Envelops, of which the following is a full, clear, concise, and exact description, reference being had to the accompanying drawings, forming a part of this specification.

My invention relates to coin receptacles, and particularly to such receptacles as are now commonly employed by savings banks to be used by depositors in receiving and retaining currency before deposit at the bank. Many devices of this class have been devised in which a substantial box or receptacle of iron or other metal has been provided, with a suitable opening or slot for the reception of coins, and a door-way through which the currency within the receptacle may be removed by the bank officials. It has been customary to provide a lock for this door, the key or combination to which has been retained in the exclusive possession of the bank officers. The slot through which currency has been inserted has been provided with a guard device such that the coins cannot be removed from the receptacle through this opening. These devices have been quite complicated and expensive of manufacture.

It is the object of my invention to provide a device for a similar purpose but which is of far greater simplicity and materially less cost in manufacture.

My invention consists essentially in an envelop, preferably constructed of some stiff and durable parchment or paper, there being an opening at one end of the envelop through which coins may be inserted. The envelop is provided with inwardly extending tongues adapted to prevent the easy removal of coins from the envelop without mutilation thereof. While the device thus provided is not one which cannot be opened by cutting or tearing, it is one in which the honor of the bank depositor is largely depended upon for the preservation of the receptacle and the saving of the currency which may have been deposited therein.

My invention will be more clearly understood by reference to the accompanying drawing in which—

Figure 1 illustrates a front view of an envelop constructed in accordance with my invention. Fig. 2 is a back view thereof. Fig.

3 illustrates a blank sheet of paper after being cut to the shape required to form the envelop. Fig. 4 is a cross sectional view taken on lines 4, 4, of Fig. 1. Fig. 5 is a similar view illustrating a modified form of tongue. Fig. 6 is a cross sectional view of such a modification taken on lines 6, 6, of Fig. 5. Fig. 7 is a top view of the envelop illustrated in Fig. 1.

Referring more particularly to Fig. 3, I have shown a blank in which the rear wall 7 and the front wall 8 may be folded one upon the other after having first folded inwardly the rear tongue 9 and the front tongue 10. The front and rear wall portions are retained in position by the flaps 11 and 12, which, as best illustrated in Fig. 2, are folded over and glued to the outside of the rear wall 7. As best illustrated in Fig. 4, the tongues 9 and 10 are folded inwardly. The opening at the top of the envelop is partially closed by catching together the side walls of the envelop by means of the metal clips 13, 13 which prevent tearing of the material of the envelop as a coin is squeezed through the opening. As best illustrated in Fig. 7, the edges of the envelop may be pressed together to cause a partial opening of the walls 7 and 8 between the upper edges of which coins 14 may then be dropped. Upon inverting the envelop, as in the act of attempting to shake a coin therefrom, it will be seen, as illustrated in Fig. 4, that the inwardly projecting tongues 9 and 10 come into contact one with the other, thereby forming pockets which prevent the escape of the coin from the envelop.

In Figs. 5 and 6 I have illustrated a modification of my invention in which each of the tongues is slotted to form teeth 15, 15, the teeth on each tongue being desirably formed so as to interlock with those on the other tongue as best illustrated in Fig. 5. Thus a means of retaining coins within the envelop is provided, which in some respects is even more efficient than that illustrated in Figs. 1, 2, 3 and 4. One side of the savings envelop may desirably be provided with a deposit slip. This slip may be formed by printing a suitable legend and blanks upon the front side of the envelop, as indicated in Fig. 1, there being shown a blank space for the name of the depositor, the number of the account and blanks in which to fill in the date and amount of deposit. These blanks may be used to indicate the amounts deposited with-

in the envelop or to indicate the amount of money removed from the envelop and deposited in the savings bank. Any other desirable form of deposit blank may be printed 5 upon the envelop.

As will be apparent, many modifications may be employed without departing from the spirit of my invention, and I do not desire to limit myself to the precise disclosure 10 herein set forth; but

Having described my invention, I claim as new and desire to secure by Letters Patent:—

An envelop cut and folded from a single piece of paper, comprising front and rear 15 walls, flaps on the side and bottom of said front wall adapted to be folded over said rear wall, whereby the sides and bottom of said envelop may be closed, a tongue extending

from the upper end of each wall and adapted to be folded on the line of the top of the envelop and to extend downwardly into the envelop, thus leaving the top of the envelop open, said tongues forming means whereby coins may enter but are prevented from being withdrawn from said envelop, and metal clips passing through said front and rear walls and through said tongues, near the top of said envelop, the distance between said clips being just large enough for the passage therebetween of coins of ordinary size. 20 25 30

In witness whereof, I hereunto subscribe my name this 2nd day of April A. D., 1903.

EDWIN F. BROWN.
